UNITED STATES PATENT OFFICE.

SYLVIE MONTÉGUT, OF PARIS, FRANCE, ASSIGNOR TO BOUÉ SOEURS, INC., A CORPORATION OF NEW YORK.

DESIGN FOR A PERFUME BOTTLE.

Application filed April 26, 1923. Serial No. 5,962. Term of patent 14 years.

To all whom it may concern:

Be it known that I, SYLVIE MONTÉGUT, a citizen of France, and a resident of Paris, Department of Seine-et-Oise, France, have invented a new, original, and ornamental Design for Perfume Bottles, of which the following is a specification, reference being had to the accompanying drawing, forming a part thereof.

In the drawings:—

The figure represents a front elevation of a perfume bottle embodying my new design.

I claim:

The ornamental design for a perfume bottle, as shown.

SYLVIE MONTÉGUT.
